UNITED STATES PATENT OFFICE.

FRED MONTE, OF NEWARK, NEW JERSEY.

DISH-WASHING MACHINE.

1,312,414.

Specification of Letters Patent.

Patented Aug. 5, 1919.

Application filed September 17, 1918. Serial No. 254,442.

To all whom it may concern:

Be it known that FRED MONTE, a citizen of the United States, residing at Newark, in the county of Essex and State of New Jersey, has invented certain new and useful Improvements in Dish-Washing Machines, of which the following is a specification.

This invention has relation to dish washing machines, and has for an object to provide a machine designed to thoroughly and efficiently cleanse a large number of dishes at a time, and which is at the same time extremely simple in construction and easily manipulated, permitting its economical manufacture.

Another object of the invention is to provide a dish washing machine including a container, a basket in which the dishes are placed, and means for elevating and depressing the basket out of and into the container whereby to cause circulation of the water through the interstices between the dishes, imparting to the basket a rotary motion, and means for continuing said rotary motion without vertical movement of the basket while the latter is in a lowermost position.

In addition to the foregoing this invention comprehends improvements in the details of construction and arrangement of parts to be hereinafter set forth and particularly pointed out in the appended claims.

In the accompanying drawings in which similar and corresponding parts are designated by the same characters of reference throughout the several views in which they appear;

Figure 1 is a view in vertical section of a dish washing machine constructed in accordance with my invention.

Fig. 2 is a view thereof in top plan with the cover of the container partly broken away, and

Fig. 3 is a view of the machine in side elevation.

With reference to the drawings 10 indicates a tank in the bottom of which is centrally located a step bearing 11. A pair of upright brackets 12 and 13 are located on the upper portion of the tank at opposite sides thereof and have their upper ends connected by a cross bar 14 having a central opening 15. A rod 16 is provided with one end set in the bearing 11 and the other extended through said opening 15 of the cross bar. A sleeve 17 more than one-half the

length of the rod surrounds the latter and extends through said opening 15. The lower end of the sleeve is formed with an enlargement 18 in which a nut 19 is held, said nut engaging threads which are formed on the lower portion of the rod. The lower end of the sleeve is also formed with a discous enlargement 20. Resting upon the cross bar 14 is a bevel gear 21 having a central opening through which the sleeve 17 passes, a feather 22 being formed upon the sleeve to lock the gear thereto but to permit the sleeve to freely pass through said gear in a vertical direction. The gear is formed with an annular groove 23, and a pair of angular plates 24 are secured to the cross bar and have their adjacent edges engaged in the groove to secure the gear in place but to permit free rotation thereof. A horizontal shaft 25 is mounted in bearings 26, the latter being secured to the cross bar. A bevel pinion 27 mounted on the shaft 25 engages the gear 21 to transmit motion thereto. A spur gear 28 is mounted on the other end of the shaft 25, and said gear engages a spur gear 29 mounted on a stub shaft which is secured to the bracket 12. A handle 30 secured to the gear 29 enables the latter to be rotated. A cover plate 31 is provided for the tank, said plate having a central opening through which the sleeve 17 passes. A valve coupling 32 is secured in the plate for connection to a hose 33, the latter resting upon a pulley 34 which is mounted on the bracket 13. Mounted at opposite sides of the tank are platforms 35 located on a level with the upper edge of the tank. To contain the dishes a circular basket 36 is provided, the same having a radio passage-way 37 formed therein extending from the center to the periphery thereof. It will also be observed that a collar 38 is secured to the sleeve 17 at a point from the lower end thereof to a distance slightly greater than the height of the basket.

In operation, the basket is rested upon one of the platforms 35 and filled with the dishes to be cleansed. The sleeve 17 should be elevated so as to dispose the disk 20 at a point coincident with the upper edge of the tank. The basket may now be slid along the platform and rested upon said plate 20, the passage way 37 receiving the sleeve 17 so that the basket may be centralized. The handle 30 is now rotated and as a result mo.

tion is transmitted through the gears 29 and 28 to shaft 25, thence through gears 27 and 21 to the sleeve 17 rotating the same. It will be obvious that as the rod 16 is fixed and in threaded connection with the sleeve, the latter will descend during rotation until the disk 20 rests upon the step bearing 11. At this point the nut 19 will have disengaged itself from the threads of the rod 16 and continued rotation of the handle 30 will cause the sleeve and basket to rotate without moving vertically. The circulation thus set up in the fluid contained in the tank will thoroughly cleanse the dishes. The water may be supplied through the hose 33. When the operation is completed the sleeve 17 is slightly elevated to cause the nut 19 to re-engage the threads of the rod 16, whereupon a reverse rotation of the handle 30 will cause the sleeve and basket to ascend. It will be apparent that upon engagement of the collar 38 with the cover plate 31, the latter will be lifted thus permitting the basket to be transferred from the disk 20 to one of the platforms 35.

While I have illustrated and described my invention with some degree of particularity I realize that in practice various alterations therein may be made. I therefore reserve the right and privilege of changing the form of the details of construction, or otherwise altering the arrangement of the correlated parts, without departing from the spirit of the invention or the scope of the appended claims.

Having thus described my invention, what

I claim as new and desire to secure by United States Letters Patent is:

1. A dish washing machine including a tank, a threaded upright, a container having a threaded connection with the upright, and means for rotating the container whereby to cause the latter to ascend or descend, the threads of the upright terminating at a point above the lower end thereof so that the container may rotate without an accompanying vertical movement when the container is in a lowermost position.

2. A dish washing machine including a tank, a threaded upright mounted therein, a sleeve embracing the upright, a threaded connection between the sleeve and rod, a disk on the sleeve, a dish container mounted on the disk, a collar mounted on the sleeve, a cover for the tank, brackets secured to the tank, a cross bar connecting the brackets and having an opening to receive the sleeve, a bevel gear mounted on the cross bar, a splined connection between the gear and sleeve, a shaft journaled on the cross bar, a bevel pinion on the shaft meshing with the gear, a spur gear on the shaft, a second spur gear journaled on one bracket meshing with the first spur gear, and means for rotating the second spur gear.

In testimony whereof I affix my signature in presence of two witnesses.

FRED MONTE.
